UNITED STATES PATENT OFFICE.

ARTHUR HIPPISLEY, OF BATH, ENGLAND.

CARBURETER.

1,006,088.

Specification of Letters Patent. Patented Oct. 17, 1911.

Application filed September 23, 1910. Serial No. 583,439.

To all whom it may concern:

Be it known that I, ARTHUR HIPPISLEY, a subject of the King of England, and resident of Ston Easton, Bath, Somersetshire, England, have invented an Improved Carbureter for Internal-Combustion Engines, of which the following is a specification.

This invention relates to carbureters having multiple jets brought into or out of use progressively.

According to this invention, the jets are arranged in a circle so as to feed inward into a central vertical air-pipe and may be covered or uncovered in pairs arranged diametrically opposite to one another. This may be effected by a rotating sleeve, with ports, or in any other convenient manner.

In the accompanying drawings; Figure 1 is a central vertical section showing the preferred method of carrying out this invention, and Fig. 2 is a transverse section on the line 2—2 of Fig. 1.

Like letters indicate like parts in both figures.

25 In this construction, a hollow annular chamber A termed a jet ring is used, and this is supplied with petrol or the like from any suitable source, as by the pipe B, a constant level being preferably maintained.

30 This jet ring has formed in its inner periphery small outlets C which constitute the jets proper. These are arranged in pairs diametrically opposite one another, and there may be any suitable number, say eight.

35 This jet ring is supported from the body of the carbureter so as to leave a concentric space D between it and the body E. The bottom of this space is provided with a perforated diaphragm F and a rotating disk G,

40 which are adapted to act as a valve. By this means the amount of air passing behind

the jets along the passages H and remaining uncarbureted can be varied to vary the richness of the mixture.

Within the jet ring A is arranged a rotating sleeve J actuated by the lever J², which ring has ports K of different lengths in the same plane as the jets C. The ports in the rotating sleeve are so arranged that as the sleeve is moved the jets are opened up or closed in pairs. The arrangement of the jets concentric with the air passages provides good carburization while the rotating sleeve enables the effective size of the fuel outlet to be easily varied.

The carbureter may be water jacketed or heated in any usual manner. For instance there may be a concentric jacket L arranged above the jet ring and resting thereon, this jacket being fed with water or hot gas.

Having fully described my invention, what I claim and desire to secure by Letters Patent is:—

The herein described carbureter, comprising the combination with the carbureter-casing, of a hollow ring A concentrically disposed within the said casing and being provided with a plurality of symmetrically arranged jet outlets, a rotatable sleeve J carried by the ring and the casing, the said sleeve forming a central air passage and having ports of different lengths adapted to progressively cover or uncover opposite jets in pairs, substantially as and for the purpose specified and shown.

In testimony whereof I have hereunto set my hand in the presence of two subscribing witnesses.

ARTHUR HIPPISLEY.
